(57) **CLAIM**

The ornamental design for an electrical air freshener, as shown and described.

DESCRIPTION

FIG. 1 is a perspective view of an electrical air freshener showing my new design;

FIG. 2 is a perspective view taken from a left frontal side thereof;

FIG. 3 is a left side elevation view thereof;

FIG. 4 is a right side elevation view thereof;

FIG. 5 is a top plan view of the container portion of the electrical air freshener shown separately for clarify of illustration;

FIG. 6 is a front elevation view of the container portion of the electrical air freshener shown separately for clarify of illustration;

FIG. 7 is a bottom plan view of the container portion of the electrical air freshener shown separately for clarify of illustration;

FIG. 8 is a rear elevation view of the container portion of the electrical air freshener shown separately for clarify of illustration;

FIG. 9 is a left side elevation view of the container portion of the electrical air freshener shown separately for clarify of illustration, the right side elevation view being a mirror image of that shown;

FIG. 10 is a rear elevation view of the body portion of the electrical air freshener shown separately for clarity of illustration;

FIG. 11 is a left side elevation view of the body portion of the electrical air freshener shown separately for clarify of illustration, the right side elevation view being a mirror image of that shown;

FIG. 12 is a top plan view of the electrical air freshener and of the body portion of the electrical air freshener shown separately for clarify of illustration;

FIG. 13 is a bottom plan view of the body portion of the electrical air freshener shown separately for clarify of illustration; and,

FIG. 14 is a front elevation view of the body portion of the electrical air freshener shown separately for clarify of illustration.
